UNITED STATES PATENT OFFICE.

JOHN W. BODYFIELD, OF HOT SPRINGS, ARKANSAS.

GAS-GENERATOR.

1,074,042.

Specification of Letters Patent. Patented Sept. 23, 1913.

Application filed November 16, 1912. Serial No. 731,777.

To all whom it may concern:

Be it known that I, JOHN W. BODYFIELD, a citizen of the United States, residing at Hot Springs, in the county of Garland and 5 State of Arkansas, have invented new and useful Improvements in Gas-Generators, of which the following is a specification.

This invention relates to acetylene gas apparatus, the object in view being to provide, 10 in connection with a suitable generator and gas holder or bell, automatic feed mechanism for successively feeding charges of carbid to the generator in accordance with the rising and falling movements of the bell 15 and the gas contained therein and delivered thereto from the generator.

With the above and other objects in view, the invention consists in the construction, combination and arrangement of parts, as 20 will be hereinafter more fully described, illustrated in the accompanying drawings, and pointed out in the claims hereunto appended.

In the drawings: Figure 1 is a vertical 25 sectional view of an acetylene generator and gas holder, showing the present invention applied thereto. Fig. 2 is a plan view of part of the hopper. Fig. 3 is a vertical section through a part of the hopper, taken at 30 right angles to Fig. 1, showing one of the buckets. Fig. 4 is a vertical section through the hopper on a smaller scale, taken at right angles to Fig. 1, showing the buckets in side elevation and the relative ar- 35 rangement of the catches. Fig. 5 is a vertical sectional view similar to Fig. 3, showing a modified form of bucket.

Referring to the drawings, 1 designates the body of the generator which is in the 40 form of a vertical cylinder closed at the bottom, as shown at 2, and provided adjacent to the bottom with a hole 3 to enable the residue to be removed therefrom. Arranged above the bottom 2 is a false bottom 4 of inverted frusto-conical form, and having a central opening 5 covered by a screen 5', through which the residue gravitates into the bottom portion of the generator, from which it may be subsequently removed. 45 Operating above the false bottom 4 is a cone-shaped stopper 6, adapted to close the opening 5 when in its lowermost position. Extending upward from the stopper 6 is a stem 7 which passes through a guide 8 and 50 outwardly through a guide tube 9 in the top 55 of the generator, where it is provided

with a suitable operating handle 11, by means of which the stopper 6 may be forced down to close the opening 5, or raised to leave said opening clear for the passage of residue through the same.

The gas holder comprises the usual cylindrical body 12, in which is arranged the lower open end of a vertically movable bell 13 adapted to rise and fall in accordance 65 with the gas contained therein. Connected to the upper part of the holder 12 is a guide frame, comprising the parallel side members 14, and cross bar 15 connecting the same at the top, the bell being provided with 70 runners or eyes 16 which embrace the guides 14 and move up and down thereon.

17 designates the gas pipe, one vertical arm of which is arranged in the generator 1, and has its open upper extremity arranged 75 above the water level, indicated at 18. The gas pipe 17 passes outwardly through the body 1 adjacent to the bottom thereof, and into the bottom portion of the gas holder, thence upward to a point above the water 80 level, whereby the gas generated is conveyed from the generator into the gas holder.

19 designates a service gas pipe which leads from the holder to the points of use. 85

20 designates a funnel or carbid magazine, from which a pipe 21 leads into the generator 1, at a point intermediate the height of the latter, as shown. After the generator is 90 filled with water up to the water level, indicated at 18, oil is placed in the upper portion of the pipe 21, so that the carbid has to pass through the oil before reaching the water contained in the generator. Within the hopper 20 is arranged a plurality of carbid 95 holding buckets 22. Under the arrangement shown in Fig. 3, each of said buckets comprises four sides, and an inclined bottom 23, each bucket being hinged to the inner wall of the funnel 20, as shown at 24, 100 and being offset from the wall of the hopper by means of wedge-shaped spacing blocks 25 which will insure the falling of the bucket 22, when released, as hereinafter described. Connected pivotally to each of the 105 buckets, at the point 26, is a catch 27 which passes through an opening 28 in the wall of the hopper, and is provided with a shoulder 29 to engage the hopper wall for the purpose of holding the bucket in an upright 110 position.

30 designates a spring for holding the

5 catch in engagement with the hopper wall. By reference to Fig. 4, it will be seen that the catches all extend beyond the plane of the outer face of the hopper wall, and are arranged at different elevations, so as to be 10 acted upon successively by a trip 31 in the form of an arm or bar secured to the top of the rising and falling bell 14, as shown in Fig. 1.

10 From the foregoing description, it will now be understood that as the gas is consumed from the bell, the latter descends, and the trip 31 comes in contact with the highest 15 catch, thereby depressing the catch and releasing the bucket controlled thereby, the bucket swinging downwardly on its hinge connection with the hopper wall and dumping the carbid contained therein into the bottom of the funnel or hopper, from whence 20 it passes through the oil and into the water contained in the generator. The gas generated thereby causes the bell to quickly ascend, and after the gas is consumed therein and the bell again descends, the trip arm 25 comes into contact with the next highest catch, causing the discharge of the carbid from the bucket controlled thereby. Any 30 number of buckets may be employed in accordance with the size of the machine and the hopper. It will be observed that the buckets are thus successively discharged, thereby maintaining the generator in operative condition, as long as any buckets 35 remain filled with carbid.

35 Instead of mounting the buckets in a manner illustrated in Fig. 3, they may be arranged as shown in Fig. 5, in which the inner inclined wall 32 of each bucket is pivotally connected to the stationary portion of 40 the bucket, as shown at 33, while the catch, indicated at 34, is pivotally connected to the hinged wall 32 at or near the bottom thereof,

as shown at 35. Otherwise the arrangement is exactly the same as shown in Figs. 3 and 4, the catches being arranged at different 45 elevations, so as to be successively operated upon by means of the trip 31.

The generator is primarily charged by filling each of the buckets with carbid, each bucket holding a sufficient quantity of carbid to produce the requisite amount of gas to fill the holder. After this, the generator is entirely automatic in operation, as indicated in the foregoing description, the buckets being successively discharged by the 50 trip carried by the rising and falling bell of the gas holder.

What is claimed is:

1. The combination with a gas generator, and a gas holder embodying a rising and falling bell, of a trip arm carried by the bell, a hopper embodying a plurality of dumping carbid holding buckets adapted for independent discharge and contained in the body of the hopper, and catches holding said 65 buckets and projecting through the outside wall of the hopper and arranged for direct actuation successively by said trip arm.

2. The combination with a gas generator, and a gas holder embodying a rising and falling bell, of a trip arm carried by the bell, a hopper, a plurality of carbid holding buckets arranged in an inclined series along a straight upright wall of the hopper, and sustaining catches for said buckets also arranged in an inclined series and adapted for 70 direct and successive actuation by said trip arm.

In testimony whereof I affix my signature in presence of two witnesses.

JOHN W. BODYFIELD.
